OPEN MESH FABRIC WOVEN WITH
SYNTHETIC YARN

Joseph Bussiere, Lewiston, Maine, assignor to Bates Manufacturing Company, a corporation of Maine

Application November 2, 1953, Serial No. 389,651

7 Claims. (Cl. 139—383)

This invention relates to open mesh fabrics and more particularly it relates to open mesh fabrics formed of synthetic yarns in which the filling and warp ends are maintained in an equidistant and parallel relationship by means of a plurality of interwoven binder threads.

When weaving open mesh fabrics with synthetic yarns, there is a marked tendency for the filling and warp ends to "bunch" or slip out of position during and after the fabric is woven. This slippage tendency, which primarily is due to the lack of a natural self-binding characteristic in synthetic yarns, is so pronounced in a plain weave that the fabric cannot be conveniently handled without disrupting the parallel and equidistant alignment of the filling and warp ends.

Several attempts have been made to overcome this problem, but none has been commercially successful. For example, a leno weave has been used in open mesh fabrics of this nature, however, it has been found that this technique at best, merely reduces the slippage tendency. Furthermore, a leno leave is undesirable for many industrial purposes.

In the production of open mesh abrasive fabric with synthetic yarns, for example, it has been found that a plain weave and other types of weaves, such as a twill weave, are preferable to a leno weave. However, because of the slippage problem, plain or twill weaves have hitherto been found impractical, for this purpose. Even if an adhesive coating is supplied to the woven fabric this difficulty is not overcome because slippage occurs in a significant degree between the time the fabric is woven and when the adhesive coating is applied. Furthermore, even with an adhesive coating, the material must be handled with great care during the subsequent production steps.

To overcome this problem, the applicant has devised a simple and effective means whereby the filling and warp ends in an open mesh fabric formed of synthetic yarns, are maintained in the proper position, even when the cloth is handled for a considerable length of time before and after a plastic coating is applied thereto. In accordance with this invention, pairs of relatively fine binder warp threads are disposed adjacent to, and on either side of each of the warp ends. The binder threads are interlaced with the filling ends and thereby hold the warp ends in position. When the fabric is woven, the binder warp threads are barely visible to the naked eye because they are partially covered by the thicker warp ends.

For a better understanding of this invention, reference may be had to the accompanying drawings in which:

Figure 1 is an enlarged schematic perspective view of a portion of a plain weave open mesh fabric including pairs of binder warp threads to hold the warp ends in position; and

Figure 2 is a planned view of an open mesh twill weave fabric woven in accordance with this invention.

With reference to Figure 1, an open mesh plain weave fabric 10 woven with synthetic yarn, is formed by a plurality of equally spaced warp ends 11 which are inter-

woven with a plurality of equally spaced filling ends 12.

Pairs of relatively fine binder warp threads 13 and 14 are disposed on either side of each of the warp ends 11 and are also interwoven in a plain weave pattern with 5 the filling ends 12. In this respect, it will be noted that the binder threads forming each pair, are interwoven in opposite sequence. For example, the binder thread 13 passes under and over the filling ends 12a and 12b, respectively, and binder thread 14 passes over and under 10 the same filling ends. The binder threads may be formed of cotton or other types of natural fibers, or of glass, rayon, nylon and other synthetic fibers.

It will be appreciated that after the fabric is woven, each pair of binder threads 13 and 14 hold one of the 15 warp ends 11, which is interposed therebetween, in position with respect to the spaced apart filling ends 12. The binder threads also serve to maintain the filling ends 12 in their proper position. In addition, it will be appreciated that the binder threads 13 and 14 are barely visible to the naked eye because they are partially covered by 20 the larger warp end 11, and each warp end and associated pair of binder threads appear as a single thread in the woven fabric. In this connection, the warp ends 11 may be formed of finer yarn than the filling ends 12 in 25 order that the total thickness of each warp end and associated pair of binder threads is approximately equal to the thickness of a single filling end.

It is to be understood that this binder thread arrangement may be utilized to bind the warp ends in other 30 types of open mesh weaves woven with synthetic yarns. For example, Figure 2 discloses an open mesh twill weave fabric 18 which may be used for the production of relatively coarse abrasive materials, and for other purposes.

The fabric 18 shown in Figure 2, is formed of a 35 plurality of equally spaced warp ends 19 which are interwoven in a twill weave pattern with a plurality of equally spaced filling ends 20. It will be noted that in a twill weave pattern, the warp end 19a passes over filling ends 20a and 20b and under filling ends 20c and 20d, etc., 40 and the next adjacent warp end 19b passes over filling end 20a and under filling ends 20b and 20c, etc. This weaving pattern is repeated throughout the fabric, thereby forming diagonally extending ridges in the woven fabric, as indicated in the drawing by the light spots on 45 the warp ends 19.

As in the previous modification, pairs of relatively fine binder warp threads 21 and 22 are disposed on either 50 side of each of the warp ends 19. Each of the binder threads 21 and 22 are interwoven in opposite sequence, in a plain weave pattern, with the filling ends 20. For example, binder thread 21 passes under and over filling ends 20a and 20b, and the adjacent binder thread 22 passes over and under the same filling ends 20a and 20b, respectively.

The binder threads 21 and 22 serve to maintain the 55 warp ends 19 in an equidistant and parallel relationship, and also hold the filling ends 20 in their proper position. In addition, the added binding effect obtained by the twill weave helps to secure the filling and warp ends 60 in position.

In the production of abrasive fabrics, for example, a protective coating of neoprene, polyethylene, vinyl-vinylidene chloride, styrene-butadiene and the like, may be applied after the fabric is woven. The coating serves to bond the filling and warp ends at their interlacing points, 65 and also to strengthen and protect the individual threads. Thereafter, the coated fabric is treated with abrasive material, the latter also being firmly bonded thereto in a suitable manner.

It is to be understood that for certain types of open mesh fabrics a single binder thread may be used in conjunction with each warp end. Also, it is to be under-

stood that the binder thread arrangement described above may be used in conjunction with other types of weaves, and that interlacing pattern of the binder threads may be varied if desired. Therefore, the form of the invention described above should be considered as illustrative and not as limiting the scope of the following claims.

I claim:

1. In an open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said warp ends and which are interwoven with said filling ends, the binder warp ends of each pair being maintained in substantially uniform lateral spacing in the plane of the weave whereby said warp ends are firmly held in spaced position in the woven fabric.

2. An open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said spaced warp ends and which are interwoven with said filling ends, the binder warp ends forming said pairs being interwoven in opposite sequence with said filling ends.

3. An open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said spaced warp ends and which are interwoven with said filling ends, at least one warp end of each of said pairs of binder warp ends being interwoven with said filling ends in different sequence with respect to the warp end interposed therebetween.

4. An open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said spaced warp ends and which are interwoven with said filling ends, said warp ends being of lesser thickness than said filling ends, and the combined thickness of a pair of binder warp ends and the warp end interposed therebetween being substantially the same as the thickness of one of said filling ends. 45

5. An open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said spaced warp ends and which are interwoven with said filling ends, said warp and filling ends being interwoven in a twill weave pattern and said pairs of binder warp ends being interwoven with said filling ends in a plain weave pattern and with the respective ends of each pair of binder warp ends being interwoven in opposite sequence.

10 6. An open mesh fabric formed of synthetic yarns which includes a plurality of spaced warp ends interwoven with a plurality of spaced filling ends, the improvement which comprises pairs of relatively fine binder warp ends disposed adjacent to and one on either side of each of said spaced warp ends and which are interwoven with said filling ends, said warp and filling ends being interwoven in a twill weave pattern and said pairs of binder warp ends being interwoven with said filling ends in a plain weave pattern and in different sequence with respect to the warp end interposed therebetween.

15 7. In an open mesh fabric formed of a plurality of spaced warp ends interwoven with a plurality of relatively thicker, spaced filling ends, the improvement which comprises a plurality of relatively fine binder warp ends, at least one of which is disposed closely adjacent each of said warp ends and which is interwoven with said filling ends in opposite sequence than the warp end associated therewith, the combined thickness of a warp end and an associated binder warp end being substantially equal to the thickness of one of said filling ends.
